UNITED STATES PATENT OFFICE.

JOSEPH H. S. DAVIS AND WILLIAM G. W. EVANS, OF KOKOMO, INDIANA.

DESIGN FOR A CARPET-HOOK.

SPECIFICATION forming part of Design No. 26,792, dated March 23, 1897.

Application filed February 3, 1897. Serial No. 621,888. Term of patent 7 years.

To all whom it may concern:

Be it known that we, JOSEPH H. S. DAVIS and WILLIAM G. W. EVANS, citizens of the United States, residing at Kokomo, in the 5 county of Howard and State of Indiana, have invented and produced a certain new and original Design for Carpet-Hooks; and we do declare the following to be a full, clear, and exact description of the invention, such as 10 will enable others skilled in the art to which it appertains to make and use the same.

Our invention has relation to a design for a carpet hook or fastener.

It relates to the entire configuration of the 15 hook, and especially to a hook made of malleable metal.

Our invention relates particularly to a carpet-hook as illustrated in the accompanying drawings, in which—

20 Figure 1 is a perspective view of a carpet-

hook embodying our design, and Fig. 2 is a side elevation of the same.

The leading features of our design appear in the following description.

1 represents the tapering pointed shank, 25 formed with an oblong rectangular head 2, on one end of which appears an upwardly and outwardly projecting pointed arm 3.

Having thus fully described our design, what we claim as new, and desire to secure by 30 Letters Patent of the United States, is—

The design for a carpet-hook, substantially as herein shown and described.

In testimony whereof we hereunto affix our signatures in presence of two witnesses.

JOSEPH H. S. DAVIS.

WILLIAM G. W. EVANS.
